METHOD OF MAKING SPRING ASSEMBLAGES

Ivar A. Morberg, Chicago, Ill., assignor to Western Electric Company, Incorporated, New York, N. Y., a corporation of New York

Application October 4, 1951, Serial No. 249,751

11 Claims. (Cl. 29—155.55)

1

This invention relates to a method of making spring assemblages for switches in which a plurality of springs are mounted on an insulating card and more particularly to a method of slitting a strip of sheet metal stock into a plurality of ribbons and simultaneously forming the springs and attaching them onto the insulating cards.

In the telephone communication field a large number of switches are used having components of spring assemblages comprising a set of a predetermined number of contact springs mounted on insulating cards. Due to the difficulty in handling narrow strips of spring material in large coils, most of these assemblages of contact springs and cards are made up by punching individual springs from wide stock and putting the springs in magazines which will feed them to the insulator cards to which they are then attached. Another method of making these spring assemblages is to successively punch the springs singly from a relatively wide strip of stock into a nest in a tray for receiving a definite number of springs in a predetermined spaced relation to each other and then advancing the tray to a station where an insulating card is positioned and then attaching the springs thereto.

It is an object of the present invention to provide an efficient and effective method of making spring assemblages.

It is a further object of the invention simultaneously to form a plurality of springs from a strip and to attach them to a card.

In accordance with one embodiment of the invention the method may be practiced by advancing a relatively wide strip of stock predetermined uniform distances step by step through various stations in a punch press, successively punching transverse rows of pilot apertures and clinching lugs in the strip at one station, punch shearing successive portions of the strip into a predetermined number of narrow ribbons, looping the ribbons and spreading them apart in a predetermined horizontally spaced relation to each other, advancing the ribbons in timed relation to the advancement of the strip, feeding insulating cards in timed relation to the advancement of the strips from a magazine positioned adjacent the path of movement of the ribbons onto the ribbons, clinching the lugs formed on the ribbons about the cards to secure successive portions of

2

the ribbons onto successive cards, and punching sections from successive portions of the ribbons to sever completed assemblages of springs from the ribbons.

Other objects and advantages of the invention will become apparent by reference to the following detailed description thereof when considered in conjunction with the accompanying drawings diagrammatically illustrating a preferred embodiment of the invention, in which

Fig. 1 is a somewhat diagrammatic plan view of the mechanism for making spring assemblages and showing the strip from which the springs are made in various stages of fabrication;

15 Figs. 2 and 2A are longitudinal sectional views taken on the lines 2—2 and 2A—2A of Fig. 1;

Fig. 3 is a cross-sectional view through the slitting punch and die taken on the line 3—3 of Fig. 1;

20 Fig. 4 is a cross-sectional view taken on the line 4—4 of Fig. 1 showing the ribbons in laterally spaced relation to each other; and

Fig. 5 is a view of the spring assemblage.

The assemblage 10 of contact springs 12 made 25 according to the method constituting the present invention is shown in Fig. 5 and comprises six similar contact springs 12 disposed in parallel relation and attached to a card of insulating material 14. Each of the contact springs 12 has a pair of lugs 16 punched therein which engage in notches 18 disposed along the side edges of the rectangular insulator card 14 and are clinched into tight engagement with the top of the card to securely attach the springs 12 to the card.

The contact springs 12 are formed from a relatively wide, flat strip of spring stock 20 (Fig. 1) which is advanced intermittently through a plurality of stations and between sets of cooperating punch and dies in a punch press 21. The strip 20 is advanced step by step uniform distances by a pair of feed rolls 22 operated in synchronism with the actuation of the press. The distance of advance of the strip 20 is greater than the length of the springs 12. At the first station a plurality of punches 24 mounted for movement with the ram (not shown) of the punch press 21 cooperate with stationary dies 26 to perforate a transverse row of pilot apertures 28 in the strip 20, and pairs of punches 30 actuated in timed relation with the movement of the ram of the

press cooperate with dies 32 to shear form two transverse rows of the clinching lugs 16. The lugs 16 after being shear formed are disposed substantially flush with the strip 20.

When the strip is advanced one step to the next station, a shearing die 42 movable with the ram of the press cooperates with a stationary die 44 to shear a longitudinal section of the strip equal to the length of forward movement thereof into a plurality of relatively narrow ribbons 46 which are the same width as that of the contact springs 12. Spring pressed stripper plates 48 and 49 on the dies 42 and 44, respectively, serve to strip the ribbons 46 from the dies and return them to their original position in substantial horizontal alignment upon completion of the shearing operation. The waste side edge portions 50 of the strip 20 (Fig. 1) may be disposed of in any suitable manner. Pilot pins 53 mounted on the upper die element 42 are engageable in the pilot holes 28 to accurately align the strip 20 relative to the dies 42 and 44.

A slight deformation is formed at 54 (Fig. 1) at the end of the slit portion of the strip 20 where the ribbons 46 connect to the unslit portion of the strip 20. The successive sections of ribbons 46 sheared by the punch and dies 42 and 44 are flat and straight except for the slight deformations 54 formed therein which are located adjacent the pilot apertures 28.

After having been sheared, the ribbons 46 are looped downwardly at 47 and upwardly to permit spreading thereof without distortion, and enter guideways 55 in a stationary block 56 for supporting the ribbons in a horizontal plane and in predetermined laterally spaced relation to each other. The ribbons are advanced in synchronism with the feeding movement of the strip 20 by any suitable feed mechanism. As disclosed herein the feed mechanism comprises an arm 58 extending transversely of and beneath the ribbons 46. The arm 58 has a plurality of pins 59 thereon for engaging in the pilot apertures 28. The arm 58 is adapted to be reciprocated by mechanism (not shown) through a predetermined stroke equal to the distance between adjacent rows of pilot apertures 28 and in its rearward or left-hand position as shown in Fig. 2A, the arm 58 is moved upwardly to cause the pins 59 thereon to enter the pilot apertures 28 after which the arm 58 is moved forwardly to advance the ribbons one step and then is moved downwardly to disengage the pins 59 from the apertures 28, after which it is moved rearwardly, in timed relation to the operation of the press.

A double row of punches 62—62 actuated in timed relation to the movement of the ram cooperates with dies 64 at the left of the feed arm 58 as viewed in Figs. 1 and 2A to engage the previously sheared attaching lugs 16 which are disposed in a substantially horizontal position and bend them upwardly to a vertical position perpendicular to the ribbons (Fig. 2A). Rows of pilot pins 66, mounted for movement with the upper dies, engage in the pilot apertures 28 of the ribbons 46 as they are advanced to accurately align the ribbons relative to the punch and dies during the successive forming operations.

A stack of cards 14 of insulating material is supported in a magazine 72 adjacent the path of travel of the ribbons 46 and the lowermost one of the stack of cards is adapted to be removed from the magazine and moved into a predetermined position above the ribbons 46 as indicated in Fig. 1. Any suitable mechanism for feeding

the lowermost insulating card into position above the ribbons 46 may be provided. The feed mechanism, diagrammatically indicated herein, includes an endless chain 73 which is mounted below the magazine 72 and has pusher elements 74 thereon, which, as the chain is driven in timed relation with the actuation of the press, engage and remove the lowermost card 14 in the magazine and move it transversely of and over the ribbons 46. The card 14 is supported for movement after it leaves the magazine 72 on the upper surfaces of a plurality of holders or supporting members 75 mounted for vertical movement in the stationary die block 76 between adjacent ribbons and yieldably held in their normal upper position by springs 77. The pusher elements 74 are adapted to disengage the end of the card 14 as the card is moved into engagement with a stop member 78 (Fig. 1) whereby the card will be supported on the holder 75 in a predetermined position above the ribbons 46 and with the notches 18 in the card in substantial vertical alignment with the lugs 16 on the ribbons 46.

Mechanism is provided for moving the card 14 down onto the ribbons and clinching the lugs 16 to secure portions of each of the ribbons 46 to the card 14. Shown somewhat diagrammatically in Fig. 2A, the mechanism includes a transverse row of plungers 80 which are slidably mounted for vertical movement with and relative to a row of blocks or members 81 and are yieldably held in their normal lower position by springs 82. The blocks 81 in turn are slidably mounted for movement in a member 83 and have a pair of pivot pins 84 extending therethrough on which are pivotally mounted pairs of clinching jaws 85 which are positioned above the ribbons 46. The blocks 81 and the jaws 85 are yieldably held in their normal down position relative to the member 83 by spring pressed plungers 87 engaging the jaws 85. The oscillatable jaws 85 which are engaged by a spring pressed plunger 88, have inwardly directed portions to maintain the jaws in their normal open position with shoulder portions 90 thereof in engagement with cam surfaces 91 formed on the member 83. Aligning pins 94 projecting downwardly from some of the movable plungers 80 are adapted to engage in aligning apertures 95 in the card 14 to accurately align the card 14 horizontally so that the notches 18 in the card 14 are in vertical alignment with the lugs 16 on the ribbons 46. As the ram of the press descends, the die member 83 and the parts carried thereby are moved downwardly therewith to cause the aligning pins 94 on the plunger 80 to enter the aligning apertures 95 in the card 14 to align the card 14 in a predetermined horizontal position, and to cause the pilot pins 66 to enter the pilot apertures 28 in the ribbons 46 to effect the proper alignment of the ribbons. As the members 80 move down they engage the card 14 and move it downwardly with the spring pressed holders 75 into engagement with the ribbons 46 and hold the card and ribbons against the lower stationary die 76. At this point the lower ends of the clinching jaws 85 are positioned behind the upstanding attaching lugs 16 on the ribbons 46 and the downward movement of the plunger 81 is arrested. Continued movement of the member 83 will cause the cam surfaces 91 to oscillate the clinching jaws 85 about the pins 84 to bend the ends of the lugs 16 over and into engagement with the upper surface of the card 14. Upon completion of the inward movement of the jaws 85 and the clinching of the lugs 16, the clinching

jaws 85 will be positioned above the lugs and the die member 83 will have moved downwardly a predetermined distance relative to the members 81 and will then engage the upper ends thereof and impart a slight downward movement to the members 81 and the clinching jaws 85, which downward movement of jaws serves to press the ends of the clinching lugs 16 firmly against the cards 14 to tightly secure the ribbons 46 to the card 14. On the upward movement of the ram and the dies the clinching jaws and pilot pins are raised to provide clearance for the forward movement of the ribbons and the cards 14 secured thereto.

At the following station a set of clipping punches 93 movable with the ram of the press cooperates with dies 96 to punch sections of scrap 98 from the ribbons and sever a complete spring assemblage 10 from the ribbons. Pilot pins 66 mounted in the punch 93, engage in the apertures 28 to accurately position the ribbons relative to the punch 93. The scrap sections 98 punched from the ribbons 46 include the pilot perforations 28 and deformations 51 in the ribbons 46. Thus, in the completed spring assemblage 10 the contact springs 12 are free of deformations therein and are securely attached to the insulator card 14 by the attaching lugs 16.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. A method of making contact spring assemblages having a plurality of contact springs mounted in spaced relation to each other on an insulator card which consists in advancing a relatively wide strip of stock successively through predetermined uniform distances, punching successive transverse rows of attaching lugs in said strip, cutting successive portions of the strip into a predetermined number of ribbons, looping the ribbons and spreading them apart in a predetermined horizontally spaced relation to each other, advancing the ribbons in timed relation to the advancement of said strip, feeding insulating cards in timed relation to the advancement of said strip onto said ribbons and between said attaching lugs thereon, clinching the lugs formed on the ribbons about the cards to secure portions of the ribbons onto said cards, and punching sections of said ribbons from said ribbons at intervals thereof to sever completed assemblages of springs from the ribbons.

2. A method of making contact spring assemblages having a plurality of contact springs mounted in spaced relation to each other on an insulator card which consists of advancing a relatively wide strip of metal stock step by step through predetermined uniform distances, punching transverse rows of attaching lugs in successive portions of said strip, punch shearing successive portions of the strip into a predetermined number of ribbons, looping the ribbons and spreading them apart in a predetermined horizontally spaced relation to each other, advancing the ribbons in timed relation to the advancement of said strip, feeding insulator cards onto successive portions of said ribbons and between the attaching lugs thereon, clinching the lugs formed on the ribbons about the cards to secure portions of the ribbons onto said cards, and punching

completed assemblages of springs from the ribbons.

3. A method of making contact spring assemblages having a plurality of contact springs mounted in spaced relation to each other on an insulator card which consists of advancing a relatively wide strip of metal stock step by step through predetermined uniform distances, punching transverse rows of attaching lugs in successive portions of said strip, punch shearing successive portions of the strip into a predetermined number of ribbons, looping the ribbons and spreading them apart in a predetermined laterally spaced relation to each other, advancing the ribbons in timed relation to the advancement of said strip, feeding insulator cards onto successive portions of said ribbons and between the attaching lugs thereon, clinching the lugs formed on the ribbons about the cards to secure portions of the ribbons onto said cards, and punching sections of said ribbons from successive portions of the ribbons to sever completed assemblages of springs from the ribbons.

4. A method of making contact spring assemblages having a plurality of contact springs mounted in spaced relation to each other on an insulator card which consists of advancing a relatively wide strip of metal stock successively through predetermined uniform distances longer than the contact springs, punching a transverse row of pilot apertures in successive portions of said strip, punching and forming rows of upstanding attaching lugs in successive portions of said strip, punch shearing successive portions of the strip into a predetermined number of ribbons, looping the ribbons and spreading them apart in a predetermined spaced apart relation to each other, advancing the ribbons in timed relation to the advancement of said strip, feeding an insulator card onto successive portions of said ribbons and between said upstanding attaching lugs thereon, clinching the lugs formed on the ribbons about the cards to secure portions of the ribbons onto said cards, and punching sections of said ribbons therefrom between adjacent cards to sever completed assemblages of springs from the ribbons.

5. A method of making contact spring assemblages having a plurality of contact springs mounted in spaced relation to each other on an insulator card which consists of intermittently advancing a relatively wide strip of stock uniform distances greater than the length of said springs to feed successive portions of said strip into successive stations, punching transverse rows of attaching lugs in successive portions of said strip at one of said stations, bending said rows of attaching lugs upwardly at one of said stations, punch shearing successive portions of the strip between adjacent ones of the attaching lugs in said rows of lugs into a predetermined number of longitudinally extending ribbons, looping the ribbons and spreading them apart in a predetermined horizontally spaced relation to each other, advancing the ribbons in timed relation to the advancement of said strip, feeding insulating cards at one of said stations onto successive portions of said ribbons and between said attaching lugs thereon, clinching the lugs formed on the ribbons about the cards at one of said stations to secure successive portions of the ribbons onto successive ones of said cards, and punching sections of said ribbons from successive portions of said ribbons at one of said stations to sever completed assemblages of springs from the ribbons.

6. A method of making contact spring assemblages having a plurality of contact springs mounted in spaced relation to each other on an insulator card which consists of intermittently advancing a relatively wide strip of metal uniform distances greater than the length of said springs to feed successive portions of said strip into successive stations, punching at one of said stations a transverse row of pilot apertures in successive portions thereof, punching transverse rows of attaching lugs in successive portions of said strip at one of said stations, bending said rows of attaching lugs upwardly at one of said stations, punch shearing successive portions of the strip between the adjacent pilot holes and adjacent attaching lugs into a predetermined number of longitudinally extending ribbons, looping the ribbons and spreading them apart between a pair of stations in a predetermined laterally spaced relation to each other, advancing the ribbons in timed relation to the advancement of said strip, feeding insulator cards at one of said stations onto successive portions of said ribbons and between the attaching lugs thereon, clinching the lugs formed on the ribbons about the cards at one of said stations to secure successive portions of the ribbons onto successive ones of said cards, punching sections of said ribbons from successive portions of said ribbons at one of said stations to sever completed assemblages of springs from the ribbons, and aligning said pilot apertures at said stations to align successive portions of said strip and said ribbons in predetermined aligned relationship relative to said stations.

7. A method of making contact spring assemblages having a plurality of contact springs mounted in spaced relation to each other on an insulator card which consists of advancing a relatively wide strip of metal stock step by step through predetermined uniform distances, punching transverse rows of attaching lugs in successive portions of said strip, cutting successive portions of the strip into a predetermined number of ribbons, spreading the ribbons apart in a predetermined horizontally spaced relation to each other, advancing the ribbons in timed relation to the advancement of said strip, feeding insulator cards onto successive portions of said ribbons and between the attaching lugs thereon, clinching the lugs formed on the ribbons about the cards to secure portions of the ribbons onto said cards, and punching completed assemblages of springs from the ribbons.

8. A method of making contact spring assemblages having a plurality of contact springs mounted in spaced relation to each other on an insulator card which consists of advancing a relatively wide strip of metal stock step by step through predetermined uniform distances, punching transverse rows of attaching lugs in successive portions of said strip, punch shearing successive portions of the strip into a predetermined number of ribbons, guiding the ribbons to predetermined spaced positions to distribute them over an appreciably larger space than the width of the original strip, advancing the ribbons in timed relation to the advancement of said strip, feeding insulator cards onto successive portions of said ribbons and between the attaching lugs thereon, clinching the lugs formed on the ribbons about the cards to secure portions of the ribbons onto said cards, and punching sections of said ribbons from successive portions of

the ribbons to sever completed assemblages of springs from the ribbons.

9. A method of making contact spring assemblages having a plurality of contact springs mounted in spaced relation to each other on an insulator card which consists of advancing a relatively wide strip of metal stock successively through predetermined uniform distances longer than the contact springs, punching a transverse row of pilot apertures in successive portions of said strip, punching and forming rows of upstanding attaching lugs in successive portions of said strip, cutting successive portions of the strip into a predetermined number of ribbons, guiding the ribbons to predetermined spaced positions to distribute them over an appreciably larger space than the width of the original strip, advancing the ribbons in timed relation to the advancement of said strip, feeding an insulator card onto successive portions of said ribbons and between said upstanding attaching lugs thereon, clinching the lugs formed on the ribbons about the cards to secure portions of the ribbons onto said cards, and punching sections of said ribbons therefrom between adjacent cards to sever completed assemblages of springs from the ribbons.

10. A method of making contact spring assemblages having a plurality of contact springs mounted in spaced relation to each other on an insulator card which consists of intermittently advancing a relatively wide strip of stock uniform distances greater than the length of said springs to feed successive portions of said strip into successive stations, punching transverse rows of attaching lugs in successive portions of said strip at one of said stations, bending said rows of attaching lugs upwardly at one of said stations, cutting successive portions of the strip between adjacent ones of the attaching lugs in said rows of lugs into a predetermined number of longitudinally extending ribbons, spreading the ribbons apart in a predetermined horizontally spaced relation to each other, advancing the ribbons in timed relation to the advancement of said strip, feeding insulating cards at one of said stations onto successive portions of said ribbons and between said attaching lugs thereon, clinching the lugs formed on the ribbons about the cards at one of said stations to secure successive portions of the ribbons onto successive ones of said cards, and punching sections of said ribbons from successive portions of said ribbons at one of said stations to sever completed assemblages of springs from the ribbons.

11. A method of making contact spring assemblages having a plurality of contact springs mounted in spaced relation to each other on an insulator card which consists of intermittently advancing a relatively wide strip of metal uniform distances greater than the length of said springs to feed successive portions of said strip into successive stations, punching at one of said stations a transverse row of pilot apertures in successive portions thereof, punching transverse rows of attaching lugs in successive portions of said strip at one of said stations, bending said rows of attaching lugs upwardly at one of said stations, cutting successive portions of the strip between the adjacent pilot holes and adjacent attaching lugs into a predetermined number of longitudinally extending ribbons, guiding the ribbons to predetermined spaced positions to distribute them over an appreciably larger space than the width of the original strip, advancing the ribbons in timed relation to the advancement

of said strip, feeding insulator cards at one of said stations onto successive portions of said ribbons and between the attaching lugs thereon, clinching the lugs formed on the ribbons about the cards at one of said stations to secure successive portions of the ribbons onto successive ones of said cards, punching sections of said ribbons from successive portions of said ribbons at one of said stations to sever completed assemblies of springs from the ribbons, and aligning 10 said pilot apertures at said stations to align successive portions of said strip and said ribbons in predetermined aligned relationship relative to said stations.
